C. BOSSE, OF WAIPAHU, TERRITORY OF HAWAII.

AUTOMATIC CAR-TRANSFER.

No. 901,488.

Specification of Letters Patent.

Patented Oct. 20, 1908.

Application filed April 25, 1907. Serial No. 370,299.

To all whom it may concern:

Be it known that I, EUGENE M. SCOVILLE, a citizen of the United States, residing at Waipahu, Island and county of Oahu, Territory of Hawaii, have invented a new and useful Automatic Car-Transfer, of which the following is a specification.

This invention relates to apparatus for transferring a car from one track to another track, and particularly to apparatus of this character suitable for transferring a cane car from the track alongside of the cane carrier of the mill, from which car the cane has been unloaded onto said carrier, to a track on which said car may be returned to the cane field. Heretofore such transfer has usually been accomplished either by switching the car or by means of a turn-table, in either case the car being usually moved by laborers in a slow and expensive manner.

This invention contemplates the transfer of such cars automatically without laborers, effecting a saving not only in labor but in the time required for such transfer.

The invention consists in the novel construction and combination of parts herein-after fully described and claimed, whereby such a transfer is accomplished in a rapid and economical manner.

Reference is to be had to the accompanying drawings, forming a part of this specification, in which similar characters of reference indicate corresponding parts in all the views.

Figure 1 is a plan view of a car transfer embodying my invention. Fig. 2 is a sectional elevation on the line A—B of Fig. 1. Fig. 3 is a sectional elevation on the line C—D of Fig. 1. Fig. 4 is an elevation of that portion of the apparatus shown on the right hand of Fig. 1.

1 represents the track on which the cars loaded with cane are brought alongside of the cane carrier 2 onto which the cane is unloaded and carried to the mill. 3 represents a car from which the cane has been unloaded onto said carrier 2, which car is to be transferred to the track 4 and returned to the cane field. The car 5 is a loaded car to replace the car 3 and be unloaded and then transferred.

A table 6 is placed at the ends of the tracks 1 and 4, and is pivoted in the boxes 7 to tilt transversely with respect to said

tracks. The boxes 7 are in line with the center-line of track 4. The tracks 1 and 4 are preferably on a slight grade, the track 1 sloping down toward the table 6, and the track 4 sloping away from the table 6. Below the table 6 and in line with center-line of track 1 is the hydraulic cylinder 8 provided with the piston 9. A piece 10 is attached to the underside of the table 6 and above the cylinder 8. The link 11 is connected to the piston 9 and to the piece 10 by the bolts 12 and 13 respectively.

A rail 14 and two shorter rails 15 16 are secured to the top of the table 6, Fig. 1. The rail 14 is practically the full length of the table, and both ends 14^a are curved upward, Fig. 2. One end 16^b of the rail 16 is similarly curved, and the other end 16^a abuts the short piece of rail 17. The corresponding end 15^a of the rail 15 abuts a like short piece of rail 18. These pieces of rail 17 18 are supported by the levers 19 20 pivoted to the table at 6^a and 6^b respectively. A counter-weight 21 is adjustably secured to each lever 19 and 20, Fig. 3. Levers 22 23 are pivoted at 6^c 6^d to the ends of the table 6. An air cylinder 24, secured to the underside and near the middle of the table 6, is provided with the piston 25, Fig. 2. The piston-rod 26 extends through both cylinder heads 24^a 24^b, and its ends 26^a 26^b are respectively connected to the lower ends of the levers 22 23. The heads 24^a 24^b are provided with a check valve 27 28 and a cock 29 30 respectively.

A transfer truck 31 is provided with an axle 32 with wheels 33 34 to run on the rails 14 16, and the axle 35 with wheels 36 37 to run on the rails 14 15 respectively. The rails 14 16 are bent slightly at 14^c 16^c, so that the transfer truck 31 is level when at the end of the table 6 over the cylinder 8, in the position shown in Fig. 2. Two transverse rails 38 are secured to the top of the truck 31, forming a short piece of track of the same gage as that of the tracks 1 and 4. One end 38^a of each of said rails 38 is curved upward.

Water in the pipe 40, under pressure from an accumulator or pump not shown, may be admitted to the cylinder 8 by opening the valve 41 in said pipe 40. Water in the cylinder 8 is allowed to escape therefrom through the pipe 42 by opening the valve 43 in said pipe 42, Fig. 3. A three-arm lever 44 is fulcrumed at 45 below the end of the

table 6 nearest the carrier 2. The piece 46 connects the lower arm 44^a of the lever 44 with the operating lever 41^a of the valve 41. The rod 47 connects the upper arm 44^b with the lever 48, fulcrumed at 49 and located so that the upper end of the lever 48 is engaged by the front end 3^a of the car 3 when said car is moved onto the truck 31 from the track 1. The valve 41 is open when the levers 44 48 are in the tilted position shown by full lines, and closed when said levers are in the normal position shown by dotted lines Fig. 3. A weight 50 secured to the arm 44^c of the lever 44 tends to pull the levers 44 48 to the normal position. This arm 44^c is engaged and held by the catch-piece 51 when the lever 44 is in the tilted position. A rod 52 depends from the table 6 and is provided with an adjustable collar 53, adapted to engage and trip the catch-piece 51 when the end of the table 6 nearest the carrier 2 is raised sufficiently. A lever 54, similar to the lever 44, is fulcrumed at 55 below the same end of the table 6 but on the opposite side of the table with respect to the fulcrum 45. Its lower arm 54^a is connected by the piece 56 to the operating lever 43^a of the valve 43. A wire rope 57, passing over the sheaves 64, connects the upper arm 54^b with the lever 58, fulcrumed at 59 and located below and alongside of the track 4, such that the upper end of the lever 58 is engaged by the platform of the car 3 when said car passes down the track 4 away from the table 6. The valve 43 is open when the levers 54 58 are in the tilted position shown by dotted lines, and closed when said levers are in the normal position shown by full lines, Fig. 3. The weight 60 on the arm 54^c tends to pull the levers 54 58 to the normal position. The arm 54^c is held by the catch-piece 61 when the lever 54 is in the tilted position. The rod 62 depends from the table 6, and the collar 63 on said rod trips the catch-piece 61 when the end of the table 6 nearest the carrier 2 is down and in the position shown in Fig. 2.

A bar 65 is pivoted on the bolt 66 to the stand 67, placed in line with track 1, but on the other side of the table 6. The end 65^a of the bar 65 is shaped so as to be first depressed by and then engage the front end 3^a of the car 3 when said car moves onto the truck 31, Fig. 3. A weight 68 is adjustably secured on the other end 65^b of said bar.

A frame 70, located between the mill and the table 6, supports a shaft 71 journaled in the boxes 72 73, and a shaft 74 journaled in the boxes 75. A drum 76 and a pulley 77 are keyed to the shaft 71. The box 73 is provided with an eccentric bushing 78 to which a lever 79 is attached. The weight 80 is adjustably secured on the lever 79. A paper or other friction wheel 81 and a pulley 82 are keyed to the shaft 74, and said shaft

is revolved by a belt 83 connecting the pulley 82 with a motor or other source of power. A rope 84 passes over the sheaves 85 86 supported from the roof of the cane shed, and one end of said rope is attached to the lever 79, and the other end to a weight 87, Figs. 1 and 4. One end of a rope 88 is attached to the drum 76, and the other end is provided with a loop or ring 88^a for attaching said rope to the hook 89 of a loaded car 5. The rope 90 passes over the sheaves 91 supported from the cane shed roof, and one end is fastened to the drum 76 and the other end to a weight 92. A brake-lever 93 is pivoted to the frame 70 so as to engage the pulley 77 when the weight 92 rests upon the end 93^a of said lever 93.

In operation, the car 3 being ready for transferring from the track 1 to track 4, the ring 88^a is placed on the hook 89 of the loaded car 5, and the operator then pulls downward on the end of the rope 84 carrying the weight 87, thereby lifting the lever 79 and turning the eccentric bushing 78 in the box 73, causing the pulley 77 to engage the friction wheel 81 and revolve the shaft 71 with the drum 76. The rope 88, in winding upon the drum 76, pulls the car 5 until it arrives at the unloading position, whereupon the operator releases his hold upon said rope 84 and applies the brake on the car 5. When the rope 84 was released, the weight 80 caused the lever 79 to lower, thereby turning the eccentric bushing 78 and disengaging the pulley 77 from the friction wheel 81. At the same time that the rope 88 was being wound upon the drum 76, the rope 90 was also being wound upon said drum, raising the weight 92. When the pulley 77 was disengaged from the friction wheel 81, the rope 90, pulled by the weight 92, in unwinding from the drum 76 reverses the direction of rotation of the shaft 71. The rope 88 is thus unwound from said drum until the weight 92 rests upon the end 93^a of the brake-lever 93 and applies said brake to the wheel 77. The operator in the mean time pulling on the ring 88^a pulls the rope 88 out to the position for hooking said ring onto the hook 89 of the next loaded car.

While the car 5 was being pulled by the rope 88, the said car pushed the car 3 towards the table 6, the brake of the car 3 being released, and the car 3 thus started continued down the inclined track 1 and onto the rails 38 on the top of the transfer truck 31, further motion of the car 3 being prevented by its front wheels engaging the curved ends 38^a of said rails. The end 65^a of the bar 65 engages the front end 3^a of the car 3 and holds said car in the position shown in Fig. 3. The front end 3^a of the car 3 has pushed the lever 48 to the tilted position, the rod 47 at the same time tilting the lever 44. The valve 41 being thereby opened, water en-

ters the cylinder 8 through the pipe 40, and the piston 9 is forced upward tilting the table 6, until the collar 53 on the rod 52 trips the catch-piece 51 and releases the arm 44^c 5 and permits the weight 50 to pull the levers 44 48 to the normal position, thereby closing the valve 41. The car 3 is thus elevated and clear of both the lever 48 and the end 63^a of the bar 65. The table 6 has thus been tilted 10 so that the portions of the rails 14 16 formerly level, and on which the truck 31 carrying the car 3 rested, now become inclined, and the truck with the car thereon runs by gravity to the pivoted end of the table. 15 Upon arriving near the end of the table, the wheels 34 37 of the truck 31 run off from the ends 16^a 15^a of the rails 16 15 onto the short rails 17 18 respectively. Before however the wheel 36 engages the curved end 14^a of the 20 rail 14, the axle 35 engages and pushes the upper end of the lever 23 with it, thereby forcing the piston 25 toward the head 24^a of the cylinder 24, air entering said cylinder behind said piston through the check valve 28 25 and cock 30 and escaping through the cock 29 in front of said piston. The retarding effect upon the truck 31 by this arrangement may be regulated, by the said cock 29 being more or less opened, so as to prevent the jar 30 which would otherwise occur when the wheel 36 engages the end 14^a of the rail 14. The weight of the truck 31 with the car 3 thereon is sufficient to overcome the counterweights 21 on the levers 19 20 when the wheels 34 37 35 rest on the short rails 17 18 respectively, and these rails are depressed thereby lowering the end of the truck 31 nearest track 4. The car 3 now runs by gravity off from the inclined rails 38 onto the track 4. The truck 31 being 40 thus relieved of the load of the car 3, the short rails 17 18 return to their normal position by the action of the counterweights 21, and the end of the truck 31 which was lowered is now raised thereby. The car 3, thus 45 started on the inclined track 4, soon engages and tilts the lever 58, which pulls on the rope 57 and tilts the lever 54, thereby opening the valve 43 allowing the water in the cylinder 8 to escape through the pipe 42. The piston 9 50 then lowers, tilting the table 6, until the collar 63 on the rod 62 tripping the catch-piece 61 releases the arm 54^c and permits the weight 60 to pull the levers 54 58 to the normal position, closing the valve 43. The table 55 6 being thus inclined, the truck 31 runs by gravity back to the end of the table nearest the carrier 2. Previous however to the wheels 33 34 of the truck 31 engaging the curved ends 14^a 16^b of the rails 14 16 respectively, the axle 32 engages and pushes the lever 22 thereby forcing the piston 25 toward the head 24^b of the cylinder 24, air entering through the check valve 27 and cock 29 and escaping through the cock 30, which is ad- 60 justed to produce the desired retarding effect 65

on the truck 31. The table 6 and truck 31 are then in position to receive the next car, Fig. 2. These operations are repeated automatically with each car.

I claim:

1. An automatic car transfer, comprising a tiltable table, a transfer truck thereon, and means for tilting said table automatically operated by the car transferred. 70
2. An automatic car transfer, comprising a tiltable table, a transfer truck thereon, means for tilting said table automatically operated by the car transferred, and means for retaining the car on said truck when it runs onto said truck at the receiving end of 80 said table.
3. An automatic car transfer, comprising a tiltable table, a transfer truck thereon, means for tilting said table automatically operated by the car, and means for retarding 85 the movement of said truck at either end of said table.
4. An automatic car transfer, comprising a tiltable table, a transfer truck thereon, means for tilting said table automatically .90 operated by the car, and means for depressing one end of said truck when carrying said car at the discharging end of said table.
5. An automatic car transfer, comprising a tiltable table, a transfer truck thereon, a fluid pressure motor for operating the tiltable table, means operated by the car moving to position on the truck for admitting pressure to said motor, and means actuated 100 by the car after the transfer has been effected for relieving pressure in the motor. 95
6. An automatic car transfer, comprising a tiltable table, a transfer truck thereon, a fluid pressure motor for operating the tilt- 105 able table, a lever system engaged by the car moving to position on the truck for operating the inlet valve of the motor, and a second lever system engaged by the car as the same leaves the truck to open the exhaust valve 110 of said motor.
7. An automatic car transfer, comprising a tiltable table, a transfer truck thereon, a fluid pressure motor for operating the tilt- 115 able table, a lever system engaged by the car moving to position on the truck for operating the inlet valve of the motor, a second lever system engaged by the car as the same leaves the truck to open the exhaust valves 120 of said motor, and means operated by the table as the same reaches its extreme positions in either direction for releasing the lever mechanism aforesaid and permitting the inlet and exhaust valves to close. 125
8. An automatic car transfer, comprising a tiltable table, a transfer truck thereon, a single continuous rail and two overlapping rail sections on said table, said rail sections having compressible end sections to cause the truck to tilt laterally and discharge the car 130

thereon, and means for tilting said table, automatically operated by the car transferred.

9. An automatic car transfer, comprising
5 a tilttable table, a transfer truck thereon, a single continuous rail and two overlapping rail sections on said table, said rail sections having depressible end sections to cause the truck to tilt laterally and discharge the car
10 theron, and counter-weights for holding said depressible end sections normally in alinement with the rail sections, and means for tilting said table automatically operated by the car transferred.
- 15 10. An automatic car transfer, comprising a tilttable table, a transfer truck thereon, means for tilting said table automatically

operated by the car, and means for retarding the movement of said truck at either end of said table, comprising pivoted levers adapted 20 to be engaged by the car, an air cylinder located below the tables, a piston therein connected to said levers and means connected with said cylinder for retarding the escape of air from the cylinder as the piston moves 25 in either direction therein.

In testimony whereof I have signed my name to this specification in the presence of two subscribing witnesses.
